UNITED STATES PATENT OFFICE.

PETER WHITE, OF ST. LOUIS, MISSOURI.

WATER-CLOSET.

SPECIFICATION forming part of Letters Patent No. 393,676, dated November 27, 1888.

Application filed May 31, 1887. Serial No. 239,762. (No model.)

To all whom it may concern:

Be it known that I, PETER WHITE, of St. Louis, Missouri, have made a new and useful Improvement in Water-Closets, of which 5 the following is a full, clear, and exact description.

In water-closets in which the contents of the bowl are removed therefrom by siphonic action this difficulty is experienced. The 10 contents are liable to be drawn upward into the air-pipe used in producing the vacuum, and as the air-pipe usually connects with the bowl-flushing pipe the deposit withdrawn from the water-closet bowl may, *via* the air- 15 exhausting pipe and the bowl-flushing pipe, in part be returned to the bowl again. To prevent this, and to insure a proper discharge of the closet, is the object of this improvement, which consists in employing a deflector 20 between the outlet from the bowl-trap and the inlet into the air-exhausting pipe so constructed and arranged as to permit of the producing of the needed vacuum, but so as to deflect the bowl-contents as they rise from the 25 bowl downward into the discharge-passage, substantially as shown in the annexed drawings, making part of this specification and exhibiting the most desirable mode of carrying out the improvement, in which—

30 Figure 1 is a vertical section on the line 1 1 of Fig. 2, which is a plan of the improved water-closet bowl. Fig. 3 is a horizontal section on the line 3 3 of Fig. 1.

The same letters of reference denote the 35 same parts.

The bowl A is of a familiar type of construction, modified only by the introduction of the improvement under consideration.

The broken line B indicates the normal 40 level at which the liquid contents of the bowl stand.

C represents the passage leading upward from the bowl, and with the bowl forming the customary upper trap.

45 D represents the air-space above the outlet from the trap, and E is the passage through which the bowl-contents, after passing the trap, are discharged, all of the customary form.

F represents the pipe through which the 50 air is exhausted (by any suitable means, not shown) from the space D, and the bowl thereby emptied.

G represents the deflector used to carry out the improvement. It is in effect a perforated 55 partition serving to divide the air-space D into a lower, d, and an upper, d', space. The perforations in the deflector are for the escape of the air upward from the space d into the space d'.

To carry out the improvement provision must be made for lifting the contents of the 60 passage C, and also for moving them sideways to be in position to fall into the passage E. To this end a suction force from two different quarters must act upon the contents from a point overhead, or substantially overhead, and from a point beyond the first-named point. Accordingly, the partition G is perforated at two different points, at g and 65 also at g'. The perforation at g is preferably in the form of a number of small perforations—say one-fourth of an inch in diameter—and grouped as shown, and the perforation g' is preferably a single one—say two 70 inches in diameter. The perforations at g are located, as shown, directly over the passage C, and the perforation g' is located as far as is practicable toward the farther end of the partition. Now when the air is exhausted 75 upward in the air-exhausting pipe F an air-draft sets from the space d in two directions—upward through the perforations g and thence through the space d' to the inlet f of the pipe F, and sideways through the space d beneath 80 the partition to the perforation g', and thence through the perforation g' to the inlet f.

The consequence is the contents of the 85 passage C are lifted above the partition which separates the passage C from the downward 90 passage beyond, and are also drawn sideways, and the resultant movement effects the discharge of the bowl-contents without drawing any portion thereof into the inlet f. After 95 the movement is well started there is apt to be a downward current setting through the perforations g', as indicated by the arrow x. The movement of the bowl-contents is mainly

as indicated by the arrow x' . The movement of the air is indicated generally by the arrow x^2 .

I claim—

- 5 A water-closet bowl having a partition separating the space D into the spaces d and d' , in combination with the air-exhausting pipe, said partition being perforated at two points,

at a point substantially above the passage C, and also at a point at or toward the farther end of the partition, substantially as and for the purpose described.

PETER WHITE.
